Attorney

UNITED STATES PATENT OFFICE

HANS CHRISTIANSEN, OF LYNN, MASSACHUSETTS, ASSIGNOR TO GEO. J. KELLY, INC.,
OF LYNN, MASSACHUSETTS, A CORPORATION OF MASSACHUSETTS

GAS LIGHTER AND THE LIKE

Application filed April 16, 1926. Serial No. 102,448.

The invention has relation to so-called igniters or lighters of the class designed for use in igniting combustible gas, vapor, or liquid by means of sparks produced through relative movement between pyrophoric material and an abrading or cutting device while engaged with each other. To a considerable extent in practice the pyrophoric material that is employed is an alloy, such as 10 an alloy of iron and cerium, or an alloy of iron and lanthanum. Usually a file-like abrading device is employed for co-operating with the pyrophoric alloy, and when relative movement of the one thereof with reference to the other is caused to take place particles of the alloy are detached in the form of sparks. Each time this action occurs, some 15 of the material of the block of alloy is worn away, and inasmuch as the block is a small one on account of the cost thereof, replacement soon becomes necessary.

The general object of the invention is to 20 make provision for convenient and ready application of a charge of pyrophoric material to the support therefor constituting an element of an igniter or lighter; also for convenient detachment of the remnant of the worn-out charge and equally convenient application of a fresh or reserve charge; and 25 also for securing retention of the charge in working relations with the said support after being applied thereto, without annoyance and inconvenience due to accidental disconnection or displacement of the charge when the igniter or lighter is operated.

The invention is illustrated in the drawings, in which,—

Fig. 1 is a side elevation of a gas lighter 30 of one of the forms to which the invention is applicable.

Fig. 2 is a bottom view of the gas lighter of Fig. 1.

Fig. 3 is a plan view of the working end 40 of the arm which carries the pyrophoric material, the latter being omitted and the view being on a scale somewhat larger than that of Figs. 1 and 2.

Fig. 4 is a side elevation, partly in section 45 on line 4; 4, of Fig. 3, of said working end

and a charge or cartridge of pyrophoric material applied thereto.

Fig. 5 is a view showing the arm in vertical cross-section on line 5; 5, of Fig. 4, with the cup of the holder for pyrophoric material partly broken away.

Fig. 6 is a plan view of the charge or cartridge of the foregoing views.

The gas lighter shown in Figs. 1 and 2 is of the same constructional type as that shown and described in U. S. Letters Patent No. 1,183,491, dated May 16, 1916. As in the said patent, the device comprises a piece of spring wire, bent to provide a pair of approximately parallel arms *a*, *b*, connected by an intermediate coil *c*, the tension of which acts with a tendency to throw the free ends of the arms away from each other, while the coil permits said arms to be relatively swung, as in other devices of this character. The arm *a* is provided with a thumb-piece *d*, produced by forming a coil in the wire, so that when the device is held in one's hand for use, with the palm of the hand resting on the upper side of the arms, pressure may be applied conveniently by the thumb against thumb-piece *d*, to press the arms transversely toward each other, the portion of said arms between the thumb-piece and the coil *c* thus acting as a hand-hold. The arm *b* has applied to the free end thereof the charge or cartridge of pyrophoric material, and the transversely bent free extremity *i* of the arm *a* has mounted revolvably thereon the abrader constituted by the round file *j*. The tension of the wire keeps the block, *g*, of pyrophoric material in contact with the abrading surface of the file, and also, normally, at one end of the file as in Fig. 2, and such tension acts to return the parts transversely to the relative position that is shown in Fig. 2 after movement of the arms *a* and *b* toward each other has been caused by pressure squeezing the arms toward each other, followed by relaxation of such pressure.

In the relative movement of the block of pyrophoric material and file back and forth lengthwise of the file, the sparking is produced through the detaching of small particles of such material. At *k* is shown the sheet-metal gas-deflecting

plate which is provided above the abrader *j*. As thus far described, the construction is as heretofore.

Preferably, in carrying the invention into effect, the holder *f* is formed with a cup, as shown best in Fig. 5, which receives within it, and grips exteriorly, one end of the block, *g*, of pyrophoric material. The said end of the block seats itself against the bottom surface within the cup. Such block, and the cup, are represented as cylindrical, but in practice they may be of any convenient and advantageous shape in cross-section.

The block, *g*, and the holder, *f*, constitute a charge or cartridge of pyrophoric material.

The holder, *f*, is combined with the block, *g*, because in practice the block itself is so small that if separate and loose it would be liable to loss. Also, it would be inconvenient to manipulate, and disconnectible direct attachment of the same to the support, in this instance the wire arm *b*, would be difficult of effective accomplishment. By combining the holder with the block of pyrophoric material, I provide a charge or cartridge of a size, character, etc., facilitating handling thereof, and also facilitating adaptation of the charge or cartridge for being conveniently connected with the supporting arm *b*, as well as for being effectually and firmly seated in connection therewith so as to ensure that the block of pyrophoric material shall remain in proper working union with such arm during working movements of the said block and the abrader with relation to each other.

I form the support for the charge or cartridge, such support being constituted herein by the arm *b*, with a divided seat, shown best in Fig. 3, adapted to receive a portion of the charge or cartridge, the said portion wedging into and spreading the divided seat and being gripped firmly thereby so as to cause the charge or cartridge to be held frictionally in place in connection with the support.

In accordance with the invention I form the divided seat at the working end of the arm *b* by doubling the free extremity of the arm back upon the main portion of the latter, keeping the two portions side by side, both in the same plane. This provides for enabling a portion of the charge or cartridge, preferably the holder, to be forced in between the two portions of the arm so as to spread the said portions slightly apart. The spring of the material causes the entered portion of the charge or cartridge to be clasped and held firmly. As one form of holder adapted to be held in place by the inherent spring of the bent-back end of arm *b* the holder *f* of the charge or cartridge is shown provided with a tang *f*³, Figs. 4 and 5, to enter between the two portions of the arm, and when such a tang is used I form in the said

portions recesses *b*⁴ registering with each other to receive the entered portion of the charge or cartridge, usually the said tang. These registering recesses form, conjointly, a split socket, one-half of such socket being constituted by a recess in one side of the main portion of the arm, and the other half thereof being constituted, as described already, by a companion recess in a portion of the arm which is doubled back upon the said main portion, in the same transverse plane with the latter. Preferably, also, I form the tang *f*³ with a taper, and the socket with a corresponding taper. The taper socket is produced by operating a tapered drill between the two portions of the working end of arm *b*. The taper of the tank facilitates the introduction of the tang by an endwise movement into the split socket, and enables the tang to become wedged within such socket. As it is pushed home within the socket, the taper tang forces the opposite sides of the seat apart slightly out of their inherent positions, so as to put the parts forming the seat under slight tension. This tension increases the frictional hold of the socket upon the tang, and more effectually safeguards against accidental dislodgment of the tang from the seat. Preferably the tang is given a conical shape, as shown. Or the holder, when of this or other shape, may be entered in the slightly flaring entrance to the space forming the divided seat, and pushed along lengthwise of the portions *b* and *b*⁴ into wedging relation.

The holder, *f*, is provided with a shoulder, *f*⁴, Figs. 4 and 5, extending outward contiguous to the basal portion of the tang. Such shoulder, *f*⁴, is adapted to rest against the surface of the support, at the side of the latter at which the block of pyrochoric material is located, so as to act as a stop when the charge or cartridge has been mounted upon arm *b* in proper working relations therewith, and so as to restrain the charge or cartridge from being tilted transversely by reason of its contact with the abrader, as a result of relative movement of the block and abrader lengthwise of the latter.

As will be apparent, a charge or cartridge like that shown in Figs. 4, 5, 6, may be applied conveniently and quickly to the supporting arm *b* by pushing the tang, *f*³, into the recesses *b*⁴. It will remain securely in place, without tendency to tip or be dragged out through engagement with the abrader during movement relative to the latter. Extraction of an expanded charge or cartridge may be effected quickly and with ease. It will be understood that in order to facilitate application of a charge or cartridge of pyrophoric material to arm *b*, or disconnection therefrom, such arm will be swung laterally clear of the abrader. The lateral swinging movement will be permitted to occur after the arm *b* has been depressed from its posi-

tion in Fig. 1 until the said arm, and a charge or cartridge carried thereby, or an exhausted holder *f*, as the case may be, have or has been moved down far enough to clear the side-arm, *m*, Fig. 1, of gas-deflector plate *k*. A similar depression of arm *b* will permit it to clear said arm in being swung laterally inward again into its working position in Figs. 1 and 2.

The free end or tip of the tang *f*³ projects through the socket and at the side of the supporting arm opposite that at which the body of the charge or cartridge is located. To safeguard said free end or tip from such contact with other objects as might operate to drive the tang endwise out of the socket, or loosen it therein, the extremity of the bent-back portion of the wire is bent downward so as to form a shield *b*⁵ close alongside the said projecting free end or tip.

20 I do not lay claim herein to the cartridge having a holder provided with a tapered tang, separately considered, inasmuch as the same is claimed in my application for U. S. Letters Patent filed April 15, 1926, Serial No. 102,340.

25 What is claimed as the invention is:—

1. In a pyrophoric igniter or lighter, the combination with an abrader, and a support that is movable relatively to the abrader, of a charge or cartridge comprising a block of 30 pyrophoric material and a holder for said block, the said holder having a tapered tang, and the said support having a divided seat which is adapted to receive said tang by an endwise movement of the tang, point first, and through being slightly spread by the wedge-like entry of the tang acts through its normal elasticity to clasp the latter so as to hold the charge or cartridge in working position in connection with the support.

35 2. A lighter having in combination relatively movable arms coacting in tong-like relation, one thereof provided with an abrader, and the other thereof having its end-portion bent back to lie alongside the main portion of such arm in spaced relation thereto, and a holder for pyrophoric material adapted to wedge into the space between the bent-back end-portion and the main portion and spread these portions outwardly from their 45 inherent positions so as to be held by the spring of the material.

50

HANS CHRISTIANSEN.
